FISHING LURE

Fred Kirkman, Solana Beach, Calif.

Application March 16, 1953, Serial No. 24,036

Term of patent 14 years

(Cl. D31—4)

To all whom it may concern:

Be it known that I, Fred Kirkman, a citizen of the United States, residing at Solana Beach, in the county of San Diego and State of California, have invented a new, original, and ornamental Design for a Fishing Lure, of which the following is a specification, reference being had to the accompanying drawing, forming a part hereof.

In the drawing:

Figure 1 is a side elevational view of a fishing lure, showing my new design;

Figure 2 is a top plan view of the lure;

Figure 3 is a side elevational view;

Figures 4, 5, and 6 are vertical cross-sectional

views taken along lines IV—IV, V—V, and VI—VI of Figure 3; and

Figure 7 is a horizontal cross-sectional view taken along line VII—VII of Figure 1.

I claim:

The ornamental design for a fishing lure, substantially as shown.

FRED KIRKMAN.
